UNITED STATES PATENT OFFICE.

SILAS A. ALDEN, OF BOSTON, MASSACHUSETTS.

ATTACHMENT FOR RIFLES.

No. 824,837.

Specification of Letters Patent.

Patented July 3, 1906.

Application filed February 13, 1905. Serial No. 245,362.

To all whom it may concern.

Be it known that I, SILAS A. ALDEN, of Boston, in the county of Suffolk and State of Massachusetts, have invented certain new and useful Improvements in Attachments for Rifles, of which the following is a specification.

This invention has for its object to provide a simple and convenient attachment adapted to hold any appliance, such as a lamp, telescope, range-finder, special sight, &c., at one side of the receiver of a rifle, the said appliance being behind the usual muzzle and breech-sights, and, if a lamp, in position to direct its rays upon the barrel and the sights.

The invention consists in the improvements which I will now proceed to describe and claim.

Of the accompanying drawings, forming a part of this specification, Figure 1 represents a side view of a rifle, having connected thereto an attachment embodying my invention having an illuminating device engaged therewith, the illuminator being shown in dotted lines. Fig. 2 represents a side view showing a different embodiment of my invention. Fig. 3 represents a top view of the embodiment of my invention shown in Fig. 2. Fig. 4 represents a side view, on a larger scale, of the attachment shown in Fig. 1, the illuminator being detached. Fig. 5 represents an edge view of the attachment shown in Fig. 4, showing a lamp attached thereto. Figs. 6 and 7 represent side and edge views of the attachment shown in Figs. 2 and 3. Fig. 8 represents a view similar to Fig. 1, showing a telescope attached to the rifle. Figs. 9 and 10 represent side views of the attachment adapted to hold a telescope. Fig. 11 represents a different form of telescope-holding attachment.

The same reference characters indicate the same parts in all the figures.

In the drawings, *a* represents the receiver of a rifle, the same having the usual flat sides *a' a'*. *b* and *b'* represent the usual sights on the barrel of the rifle.

In carrying out my invention I provide an attachment comprising a coupling member *d²*, adapted to engage a complemental coupling member on a lamp, telescope, range-finder, special sight, or other appliance to be supported by a rifle and provided with means for detachable connection with the receiver *a*. In this embodiment of my invention I have shown as the said means a clamp *d*,

which is preferably a U-shaped piece of metal adapted to bestride the receiver, its arms being provided with bearing-faces *d' d'*, formed to fit the flat sides *a' a'* of the receiver, 60 said arms being widened at their lower ends to afford an increased bearing-surface against the receiver. By this arrangement when the clamp is in place on the receiver it will bear firmly thereon without any tendency to 65 wobble. On the outer side of one of the arms of the clamp is formed the coupling member *d²*, which, in its simplest form, is a dovetail enlargement of said arm. The appliance to be supported by the clamp, in this case a lamp 70 *c*, is supported by a carrier provided with a complemental coupling member *c²*, formed to engage the member *d²*, said members establishing a firm connection between the clamp and the lamp, whereby the lamp is 75 held firmly in a position determined by the position of the clamp upon the receiver. In this embodiment of my invention the coupling members *c²* and *d²* are so arranged relatively to the bearing-faces *d' d'* of the clamp 80 that when the clamp is applied to the receiver the coupling member will hold the appliance in proper relation to the rifle. For instance, if, as in this case, the appliance is an illuminating apparatus it will hold the same at one side 85 of the receiver and in position to direct the rays along and across the barrel of the rifle and upon the sights *b b'*. The arms of the clamp are extended to project from the sides of the receiver sufficiently to engage a 90 device for exerting inward pressure on the arms, and thus causing them to positively grip or engage the sides of the receiver. Said device is preferably a bolt *s*, having a head *s'* at one end formed to bear on the outer side of 95 one of the arms, its opposite end portion being screw-threaded to engage a tapped orifice in the other arm.

The coupling member *d²* may be formed on one of the arms of the clamp, as shown in 100 Figs. 1, 4, and 5, or it may be offset from the clamp, as shown in Figs. 2, 3, 6, and 7, by an arm *d³*, formed or affixed to one of the arms of the clamp, the coupling member *d²* being formed on or affixed to the outer end of the 105 arm *d³*.

It will be seen that the described attachment is adapted to be readily applied to and removed from a rifle and that it is extremely simple and can be readily packed in small 110 compass, so that a sportsman can readily include it in his outfit.

I do not limit myself to the details of construction here shown and may variously modify the same without departing from the spirit of my invention.

5 It is obvious that the coupling member d^2 may be formed for application to some other part of a rifle and may be positively attached by screws or otherwise. I prefer to secure the coupling member by a clamp, as here 10 shown, the attachment as a whole, including the coupling member and the clamp, being simple, durable, and convenient and requiring no adaptation of the receiver, such as the formation of screw-holes therein. The 15 clamp does not interfere with the operation of any of the movable parts of the action of the rifle nor with the operation of ejecting shells. The coupling member may be used for connecting any other desired appliance, 20 such as a telescope, range-finder, special sight, &c., to a rifle.

In Fig. 8 I show a telescope e connected to a rifle by my attachment and in Figs. 9, 10, and 11 constructions of the attachment 25 adapted to secure the telescope. That in Fig. 9 has a portion d^4 adapted to embrace the receiver of the rifle and a portion d^5 to surround the tube of the telescope. Fig. 10 shows the attachment for holding the end of 30 the tube nearest the muzzle of the rifle, in which d^5 is the part surrounding the telescope-tube and d^6 that for engaging the barrel. The part d^5 in these constructions is the 35 coupling member engaging the telescope. In each case a bolt s clamps the attachment to the rifle, while bolts s^2 between the parts engaging, respectively, the telescope and rifle bind the attachment to the telescope.

When the telescope is mounted on the 40 attachment d , (shown in Figs. 1, 4, and 5,) the holder shown in Fig. 11 is used. This holder has a shank or carrier f , a band f' to surround the telescope-tube, to which it is secured by a set-screw or other clamp f^2 , and 45 dovetail coupling member f^3 , adapted to engage and slide on the member d^2 , being adjustable thereon. It is retained in adjusted position by a clamp or set-screw f^4 .

I use the term "rifle" herein in a broad sense as designating any firearm adapted to 50 be held like a rifle in firing.

I claim—

1. An attachment for firearms comprising a clamp, one of its side members being provided with an enlargement, securing means 55 for said clamp, and a dovetail coupling member carried by said enlargement.

2. An attachment for firearms comprising a clamp the side members of which are provided with bearing-faces, securing means for 60 said clamp, and a dovetail coupling member carried by one of the side members of said clamp.

3. An attachment for firearms comprising a clamp, one of the sides of said clamp being 65 provided with a dovetail enlargement forming a coupling member.

4. An attachment for firearms comprising a clamp, one of the sides of said clamp being widened to form an integral coupling member, and securing means for said clamp. 70

5. An attachment for firearms comprising a clamp, the sides of said clamp being widened at their lower ends to form bearing-surfaces, and a coupling member carried by 75 one of the sides of said clamp.

6. An attachment for firearms comprising a clamp, a coupling member carried thereby, and a carrier having frictional engagement with said coupling member. 80

7. An attachment for firearms comprising a clamp, a dovetail coupling member carried thereby, and a carrier provided with a dovetail member for engaging said coupling member. 85

8. An attachment for firearms comprising a U-shaped clamp, one member of which is provided with a lateral enlargement to form a coupling member, and a screw connecting the free ends of said clamp. 90

In testimony whereof I have affixed my signature in presence of two witnesses.

SILAS A. ALDEN.
